CLOTHESPIN

Joseph Meyer, Rugby, N. Dak.

Application June 2, 1949, Serial No. 96,772

3 Claims. (Cl. 24—137)

1

This invention relates to new and useful improvements in a clothes pin, more particularly a locking clothes pin adapted to clamp clothing securely in position on the clothes line.

The primary object of this invention is to provide a locking clothes pin simple and easy to operate.

Another important object is to provide a strong, durable clothes pin using a minimum number of parts.

Still another object is to provide a locking clothes pin easily taken completely apart so as to permit replacement of broken parts.

Further ancillary objects and advantages will appear as the description proceeds.

Reference is had to the accompanying drawings in which:

Figure 1 is a side elevation in operative position with clothes line and clothes included in cross section;

Figure 2 is a side elevation in inoperative position;

Figure 3 is a cross-section taken substantially upon line 3—3 of Figure 2;

Figure 4 is a vertical cross-section taken substantially upon the line 4—4 of Figure 1;

Figure 5 is a perspective view of the cam member.

Referring more specifically to the drawings, the numeral 10 denotes the clothes pin generally, which is composed of a body portion 12 and jaws 14 extending from the body 12.

About midway the length of the jaws 14 a stirrup 16 encompasses the jaws 14. The stirrup 16 is provided with bent open ends 18 which are journaled in a cam member 20. The cam member 20 is held against one of the jaws as shown best in Figures 1 and 2.

On the jaw opposite the jaw adjacent the cam member 20, there is a lateral groove 21 in the edges and extending along the outside surface of the jaw. This groove provides a seat for the stirrup 16, thus retaining the parts of the assembled locking clothes pin in position.

It will be seen in Figure 5 that the hole 22, in which the stirrup ends 18 are journaled, is eccentrically located relative to the medial plane of the cam member for a purpose later to be described. The cam member 20 has longitudinally extending portions 24 also for purposes later to be described.

As the body 12 and jaws 14 are of integral construction, they may be fashioned from a single block or molded as a unit. The only restriction regarding the body 12 and jaws 14 is that one of

2

the jaws must be resilient. When in relaxed relation to each other, the jaws 14 will be approximately parallel to each other and in the open position.

In the preferred construction shown, it is desirable to fashion the stirrups 16 from a resilient material. With the stirrup 16 made of a springy substance, it is a simple matter to disassemble the locking clothes pin. This is done by pulling the ends 18 from the holes 22 in the cam member in which the ends 18 are journaled and simply lifting out the cam member 20. The stirrup 16 now fits loosely about the jaws 14 and may easily be slid therefrom. It is easily seen that re-assembly is accomplished by simply reversing the steps just outlined.

It will be seen by referring to Figures 1, 2 and 5 that the eccentric location of the hole 22 in the cam member 20 allows the cam to occupy either of two stable positions relative to the other parts of the locking clothes pin. One of these stable conditions exists when the clothes pin is locked in a closed position and the other stable condition exists when the clothes pin is in the open position. As the cam is manipulated from one stable position to the other, it moves with a snap action past dead center. The reason for the snap action and the stability of the open and closed positions resides in the variation of the radial distance from the hole 22 to the plane of contact with the adjacent jaw 14, and the tension of the jaw 14 pulling the cam snugly against this plane. It is obvious that minimum radial distances provide the stable positions for the cam 20, and the tension will cause the cam to quickly rotate to such a position. It is seen in Figures 1 and 2 that the cam surface is of such a character as to have such minimums at the open and closed position, thus affording the snap action. The eccentrically located hole 22 accounts for the fact that the radial distance, as clearly seen on comparing Figures 1 and 2, is greater in the closed position than in the open position, and is the reason for the jaws 14 being closed in Figure 1 and open in Figure 2. The extensions 24 limit the cam 20 rotation between the open and closed position, and provide convenient parts for finger manipulation of the cam 20.

From the foregoing description it is believed that the operation of the locking clothes pin will be readily understood. With clothing 28 supported in the conventional manner by a clothes line 26, the open clothes pin is passed over the clothing 28 and line 26 in the usual manner to a position where the clothes line 26 passes through

and between the jaws 14 at a point approximately midway the length of the jaws 14. Extension 24 most remote from the adjacent jaw 14 of the clothes pin is then pressed in towards the clothes pin by the use of the finger. By this simple operation a clothes pin holds the clothing to the line in a firm position, sufficient pressure being exerted on the jaws to prevent the pin from slipping off the line or the clothing being torn by the wind from between the jaws.

The opening of the pin and removal from the clothes line is equally as simple. This again is accomplished by pressing the extension 24 most remote from the jaw 14, which rotates the arm member to the open position, thus releasing the pressure exerted upon the clothes line by the jaws. The clothes pin may now easily be removed from the clothes line.

This locking clothes pin is very inexpensive to produce, as it has only three component parts. Other advantages stem from the small number of parts required for this clothes pin, for instance, the small number of parts contributes materially to the simplicity of the procedure for assembly and disassembly, thus making feasible replacement of broken parts by the user.

The present embodiment of the invention has been described in considerable detail, however, it is intended that all matters contained in the foregoing specification and accompanying drawings, shall be interpreted as illustrative and not in a limitative or restricting sense.

Having described the invention, what is claimed as new is:

1. A clothes pin comprising a pair of opposed jaws for clamping a clothes line and clothing supported thereon, a combined means for urging closing movement of the jaws and for limiting opening movement of the jaws, said combined means comprising a cam body having a raised, arcuately surfaced portion spaced inwardly from its oppositely extending ends, and means engaging one of said jaws and pivoted to the body eccentrically of the raised portion, said arcuate surface slidably bearing against the other of said jaws, with the extending ends of the body constituting stops engageable with the other jaw limiting rotation of the body relative thereto and also constituting extensions that may be alternatively pressed by a finger towards the other jaw to rotate the cam body.

2. A clothes pin comprising a clothes line and clothing supported thereon, said jaws being resiliently biased apart, a combined means for urging closing movement of the jaws and for limiting opening movement of the jaws, said combined means comprising a cam body having a raised, arcuately surfaced portion spaced inwardly from its oppositely extending ends, and means engaging one of said jaws and pivoted to the body eccentrically of the raised portion, said arcuate surface slidably bearing against the other of said jaws, with the extending ends of the body constituting stops engageable with the other jaw limiting rotation of the body relative thereto and also constituting extensions that may be alternatively pressed by a finger towards the other jaw to rotate the cam body, said other jaw co-acting with the arcuate surface of the body and the eccentric pivotal connection thereof to rotate the body to a position limited by one of the ends thereof.

3. A clothes pin comprising a pair of opposed jaws for clamping a clothes line and clothing supported thereon, a combined means for urging closing movement of the jaws and for limiting opening movement of the jaws, said combined means comprising a cam body having a raised, arcuately surfaced portion spaced inwardly from its oppositely extending ends, and means engaging one of said jaws and pivoted to the body eccentrically of the raised portion, said second means comprising a stirrup encompassing said jaws, said arcuate surface slidably bearing against the other of said jaws, with the extending ends of the body constituting stops engageable with the other jaw limiting rotation of the body relative thereto and also constituting extensions that may be alternatively pressed by a finger towards the other jaw to rotate the cam body.
